UNITED STATES PATENT OFFICE.

JAMES McINTYRE, OF EDMONTON, CANADA.

FOLDING SCAFFOLD-BRACKET.

No. 809,973.

Specification of Letters Patent.

Patented Jan. 16, 1906.

Application filed May 29, 1905, Serial No. 262,829.

To all whom it may concern.

Be it known that I, JAMES McINTYRE, a subject of the King of Great Britain, residing at Edmonton, District of Alberta, North-West Territories, Canada, have invented a certain new and useful Improvement in Folding Scaffold-Brackets, of which the following is a specification, reference being had to the accompanying drawings, which form a part of this specification.

My invention has for its object to provide a novel folding scaffold-bracket of simple and economical construction and of superior utility.

The desirability of a scaffold-bracket which will be permanent, durable, easily folded up, and readily set up for use is apparent.

I carry out my invention as hereinafter described and claimed, and illustrated in the accompanying drawings, in which—

Figure 1 is a view of the device in side elevation in position for use. Fig. 2 is a view in side elevation, showing the bracket in folded position. Fig. 3 is a detail view in perspective, showing a portion of the device; and Fig. 4 is an end view of the bracket-head.

A bracket-head *a* is employed formed with bands *b b* to receive the inner end of a supporting-arm *c*. One end of the bracket-head is constructed in the form of a hook *d*, to engage the lumber already in place upon a side of the building, as shown in Fig. 1. While I have shown the bracket-head provided with a hook, I would have it understood that I do not limit myself solely thereto, as the bracket-head may be engaged in place in any suitable manner within the scope of my invention. The inner end of the supporting-arm is preferably bolted to the bracket-head between the bands *b b*, as shown at *e*. The bracket-head is also provided with ears *f*, to which may be fulcrumed, as indicated at *h*, a swinging brace *g*. Toward the outer end of the supporting-arm *c* I locate thereupon a coupling *j*, said coupling preferably constructed with a band *k*, through which is passed the outer end of the supporting-arm. Said coupling is also provided with ears on its under side, to which may be fulcrumed a supporting-brace *m*, as indicated at *n*. The lower end of the swinging brace *g* is provided with a band or stirrup *i*, through which the inner end of the supporting-brace is passed, the supporting-brace being constructed with a shoulder *p*, against which the stirrup may engage to hold the

two adjacent parts firmly in position. I prefer that the hook *d* should be provided with a downwardly-projecting flange *q* to form a substantial bearing against the lumber already upon the building and also that said bracket-head should be extended transversely of the supporting-arm, as indicated at *r r*, Fig. 4, also to form a substantial bearing.

It will be evident that the supporting-brace *m* and the swinging brace *g* may be folded up under the supporting-arm when the bracket is not in use, as indicated in Fig. 2. This is readily accomplished by lifting the supporting-brace upward within the stirrup or band *i*, so as to permit the stirrup or band to slide over the shoulder *p*, said stirrup or band folding up under the supporting-arm adjacent to the outer coupling *j*. The lower end of the supporting-brace *m* is constructed to engage against the outer face of the building upon which it may be placed, as indicated in Fig. 1. It is will be evident that when the stirrup *i* is engaged against the shoulder *p* and the bracket-head is engaged in place, as described, the supporting-arm *c* will be effectually braced and held in place against a building. Obviously the greater the weight upon the scaffold-bracket the more firmly will it be held in place. It is also obvious that the device may readily be taken down and set up and when in folded position it may be readily transported and stored in compact form.

What I claim as my invention is—

1. A folding scaffold-bracket comprising a horizontal supporting-arm, a folding supporting-brace jointedly connected with said arm toward the outer end thereof, a swinging brace jointedly connected with the supporting-arm toward the inner end thereof, said supporting-brace formed with a shoulder intermediate ends thereof, and said swinging brace with a stirrup or loop to encircle the supporting-brace and to engage the shoulder to hold the two braces in working position, the supporting-arm provided with means for engaging the same in place upon a building.

2. A folding scaffold-bracket comprising a supporting-arm, a folding supporting-brace, a coupling toward the outer end of the supporting-arm to which the supporting-brace is jointedly connected, a bracket-head upon the opposite end of the supporting-arm, and a swinging brace jointedly connected with the bracket-head, and provided with a stirrup at its opposite end encircling the sup-

porting-brace, said supporting-brace provided with a shoulder to engage the stirrup, said bracket-head constructed to be engaged upon a building.

- 5 3. A folding scaffold-bracket comprising a supporting-arm, a folding supporting-brace, a coupling toward the outer end of the supporting-arm to which the supporting-brace is jointedly connected, a bracket-head upon
- 10 the opposite end of the supporting-arm provided with bands spaced one from the other to receive the inner end of the supporting-arm, a swinging brace jointedly connected with the bracket-head and provided
- 15 with a stirrup at its outer extremity encircling the supporting-brace, means passed

through the inner end of the supporting-arm and bracket-head between said bands to connect said arm with the head, the supporting-brace provided with a shoulder to engage the swinging brace and said bracket-head constructed with a hook to engage the side of a building substantially as and in the manner described.

In testimony whereof I have signed this 25 specification in the presence of two subscribing witnesses.

JAMES McINTYRE.
